UNITED STATES PATENT OFFICE.

JAMES R. HAYES, OF ST. JOSEPH, MICHIGAN.

LOAF CATCHER FOR BREAD-WRAPPING MACHINES.

Application filed December 1, 1921. Serial No. 519,186.

To all whom it may concern:

Be it known that I, JAMES R. HAYES, a citizen of the United States, residing at St. Joseph, in the county of Berrien and State 5 of Michigan, have invented certain new and useful Improvements in Loaf Catchers for Bread-Wrapping Machines, of which the following is a specification.

This invention is an attachment for bread-wrapping machines and has for its object the provision of a novel construction whereby as the loaf is raised by the elevator of the machine it will be caught and held without any tendency to choke the operation of the parts. 10 Considerable difficulty has been experienced heretofore by the loaf catching upon the supporting element and clogging the operation of the same so that the continuity of action was interrupted and the loaf frequently 15 seriously damaged. It is the object of my invention to provide an improved mechanism whereby the parts which support the loaf will be out of the path of the same until the loaf has reached the limit of its upward 20 movement, whereupon the pressure of the loaf upon upper clamping plates will cause the supports to swing under the loaf and at the same time form the side folds in the wrapper. The invention is illustrated in the 25 accompanying drawings and will be herein- 30 after fully set forth.

In the drawings—

Figure 1 is an end elevation of my improved loaf catcher showing the parts in the 35 position assumed when the loaf is being fed between the supporting members;

Fig. 2 is a similar view showing the loaf in supported position;

Fig. 3 is a front elevation of one of the 40 supporting heads or catcher;

Fig. 4 is a rear view of the same;

Fig. 5 is a transverse section on the line 5—5 of Fig. 4.

The loaf catcher is suspended from a suitable framework which comprises bars 1 45 slidably mounted upon the frame of the bread-wrapping machine and actuated by pitmen 2 which are operatively connected with the main driving shaft of the wrapping machine. Brackets or hangers 3 depend from the suspending frame and to the lower ends of these brackets, I secure the loaf-catching and holding devices which constitute the subject-matter of my invention. At 50 the lower end of each bracket 3 is a bearing arm 4 in which is carried a rod 5, the ends

of the rod projecting through the bearings furnished by the respective arms and being secured in lugs 6 on the back of the lower plate 7. The bearing arms 4 may be integral with the respective hangers 3 and, between the arms, the lower ends of the hangers are connected by a plate 30 whereby they are held in fixed spaced relation. Upon this connecting plate, a keeper or retaining plate 31 is removably secured by a set bolt 32, the lower end of said keeper being disposed immediately over the rod 5. As shown most clearly in Fig. 5, the lower ends of the bearing arms are in the form of hooks in which the rod 5 is seated, the keeper plate 31 normally preventing the rod rising out of the hooks. Should it be desired to change the working members of the loaf-catcher, as when small loaves are to be wrapped, the keeper 31 is removed, after which the rod 5 may be lifted from the arms 4 in an obvious manner.

At the ends of the plate 7 and at the upper corners of the same, lugs or arms 8 project outwardly therefrom and in the said lugs are received the ends of the rocking bar 9. Between the lugs 8 and adjacent the respective lugs, rocker arms 10 are secured to the rocking bar 9 and the ends of these rocker arms are extended inwardly, as clearly shown at 11 and 12 respectively. To the upper extremities 11 of the rocker arms, I secure the upper pressure plate 13 so that pressure exerted upon the face of the said plate will force the same outwardly and rock the arms 10 so that the lower extremities 12 thereof will be carried inwardly and will project beyond the plate 7, as clearly shown in Fig. 5. Mounted in the lower extremities 12 of the 95 rocker arms for relative rotation is a roller 14 which, when the parts are in the position shown in Figs. 2 and 5, will project under the loaf, indicated at 15, and support the same, it being readily noted from Figs. 1 and 2 that these supports are provided in duplicate and act upon the opposite sides of the loaf. The lower terminals 12 of the rocker arms are held normally in the positions shown in Fig. 1, so that the rollers 14 will be out of the path of the rising loaf, by the springs 16 which have their intermediate portions coiled around the rocker bar 9, as shown at 17, and their ends secured respectively to the adjacent rocker arm and the plate 7 below the rocker bar 9. The force of the spring is, therefore, constantly ex-

ertered to hold the rocker arm in the position shown in Fig. 1 with the upper plate 13 projecting into the path of the loaf and the roller 14 disposed outwardly relative to the plate 7. The plates 7 and 13 are preferably provided with ribs 18 upon their working faces which are adapted to slightly indent the loaf and thereby aid in supporting the same.

10 In the particular bread-wrapping machine to which my invention has been applied, the loaf 15 is raised by an elevator, indicated conventionally at 19, so as to pass between co-operating loaf-catching and holding devices. A wrapping sheet 20 is placed over the loaf as it is raised by the elevator and, as the loaf passes between the plates 7 of the loaf catchers, the side portions of the wrappers will be folded close 20 against the sides of the loaf in an obvious manner. Upon reference to Figs. 1 and 2, it will be readily noted that, as the loaf moves upwardly, the upper side corners thereof will impinge against the inwardly 25 projecting upper plates 13 and will force them outwardly, the result being that the rocker arms are swung about their pivotal supports and the lower ends of said arms, carrying the rollers 14, are forced inwardly 30 under the loaf. The rollers being out of the path of the rising loaf, of course, offer no obstruction to its progress and choking of the operation is, therefore, avoided. The parts are so timed that just as the rollers 35 swing under the lower longitudinal edges or corners of the loaf, the elevator 19 will begin its descent so that the side portions of the wrapper will be folded under the loaf, as will be readily understood. About 40 the time that the side portions of the wrapper are folded under the loaf, the pitmen or pitmen 2 are actuated by the main driving mechanism to move the sliding bars 1 in their bearings and cause the sustaining 45 frame to travel to the point where the end folds of the wrapper are made. When the end-folding mechanism begins to act upon the wrapper, the loaf is moved out from between the plates 7 and the catchers are re- 50 turned to their initial positions to receive and support another loaf.

From the foregoing description, taken in connection with the accompanying drawings, it will be seen that I have provided a 55 very simple and efficient mechanism whereby baked loaves will be supported while the initial folds of a wrapper are produced and may be transferred without loss to mechanism for producing end folds in the wrap- 60 per and sealing the same. My mechanism is positive and certain in its action and is composed of few parts which are simple in their construction and arrangement so that

they are not liable to get out of order and they may be readily applied to any wrapping machine in which the article to be wrapped is carried into position between two mating co-operating mechanisms.

Having thus described the invention, 70 what is claimed as new is:

1. Means for the purpose set forth comprising relatively stationary plates to engage the opposite sides of a loaf, rocker arms carried by said plates, presser plates carried by the upper ends of said rocker arms and disposed normally in the path of the loaf, and loaf supports carried by the lower ends of the rocker arms and disposed normally out of the path of the loaf.

2. Means for the purpose set forth comprising a pair of co-operating relatively stationary plates adapted to engage the opposite sides of a loaf, means carried by said plates and disposed below the same to support a loaf, said means being normally out of the path of the loaf, and means carried by said plates and disposed above the same adapted to receive pressure from the loaf whereby to project the supporting means under the loaf.

3. Means for the purpose set forth comprising a pair of co-operating mating relatively stationary plates adapted to engage the opposite sides of a loaf, rocker arms mounted upon the outer sides of said plates and having their terminals projected inwardly above and below the plates, pressure plates carried by the upper terminals of said rocker arms and normally disposed over the upper edges of the relatively stationary plates and in the path of a loaf fed between said plates, supporting rollers carried by the lower terminals of the rocker arms and adapted to be projected under the loaf when the pressure plates are engaged by the loaf, and springs coiled around the fulcrums of the rocker arms and having their ends secured respectively to the rocker arms and the relatively stationary plates whereby to hold the pressure plates normally in the path of the loaf and the supporting rollers normally out of said path.

4. Means for the purpose set forth comprising hangers, bearing hooks carried by said hangers, a supporting rod engaged in said hooks, removable means for retaining the rod in the hooks, a clamping plate carried by said rod, a rocker mounted on said plate, rocker arms secured to said rocker and projecting above and below the clamping plate, a pressure plate carried by the upper ends of the rocker arms, and a loaf support carried by the lower ends of said arms.

In testimony whereof I affix my signature. 125
JAMES R. HAYES. [L. s.]
